CATALYTIC DEHYDROGENATION OF
PARAFFINS

John W. Myers, Bartlesville, Okla., assignor to
Phillips Petroleum Company, a corporation of
Delaware

No Drawing. Application February 28, 1949,
Serial No. 78,891

8 Claims. (Cl. 260—683.3)

1

This invention relates to the catalytic dehydrogenation of paraffin hydrocarbons to produce olefins and diolefins. In one of its more specific aspects it relates to an improved process for the dehydrogenation of aliphatic paraffin hydrocarbons in the presence of steam and steam insensitive alumina-metal oxide catalysts to produce the corresponding olefins and diolefins and is particularly applicable to the production of olefins and diolefins from aliphatic paraffins containing from four to five carbon atoms per molecule.

In the dehydrogenation of paraffins to the corresponding diolefins, two dehydrogenation steps are customarily employed. In the first step the paraffins are dehydrogenated to olefins which are then subjected in a second step to a separate dehydrogenation treatment to produce diolefins. The olefins may or may not be separated from the effluent of the first dehydrogenation step prior to dehydrogenation to diolefins.

The customary procedure for the production of diolefins by dehydrogenation of corresponding paraffins involves separate dehydrogenation of paraffins and olefins using somewhat different conditions for each dehydrogenation reaction. The paraffins are first dehydrogenated to olefins in the presence of a highly active dehydrogenation catalyst, the olefins are separated from the effluent of the paraffin dehydrogenation step, and separately converted to the corresponding diolefin at a temperature somewhat higher and in the presence of a less active dehydrogenation catalyst than employed for the paraffin dehydrogenation step. Chromium oxide is the active dehydrogenation catalyst conventionally used for the dehydrogenation of paraffins but it is much too severe for olefin dehydrogenation. Separate dehydrogenation of paraffins and olefins requires the use of difficult and relatively expensive separation steps to segregate the paraffin and olefin feed stocks, but the separation procedure is justified on the basis of improved yields and operation.

In the dehydrogenation of paraffins some diolefins are formed; however, the dehydrogenation of paraffins directly to diolefins is not practical by present dehydrogenation processes. Attempted combinations of concurrent dehydrogenation reactions involved in converting paraffins to diolefins in a single dehydrogenation step encounter serious difficulty due to the fact that optimum conditions for the conversion of paraffins to olefins are quite different from the optimum conditions for the conversion of olefins to diolefins.

2

For the dehydrogenation of paraffins, such as normal butane, the catalyst ordinarily employed comprises approximately 10 weight per cent chromium oxide (Cr_2O_3) deposited on a suitable carrier, such as aluminum oxide. As might be expected from the law of mass action, the dehydrogenation reaction is favored by low absolute or partial pressures. Low absolute pressures, i. e., below atmospheric pressure, while favorable to the dehydrogenation reactions, are undesirable in commercial operations due to the difficulty of preventing leakage of air into the system. For this reason it is customary to employ pressures somewhat above atmospheric pressure, generally 10 in the neighborhood of about 30 pounds per square inch gage. A low partial pressure of the reactants, e. g., normal butane, may be obtained by dilution with an inert gas. It has been found that steam is undesirable as a diluent for the dehydrogenation of paraffins since it poisons or reduces the activity and life of the chromium oxide catalyst of the conventional type. While other gaseous diluents, such as propane and lighter hydrocarbons, are not subject to this disadvantage they are generally not employed because the handling and recycling of large amounts of gaseous diluents represents a large item in plant investment and operating cost. The dehydrogenation of paraffins containing four or five carbon atoms per molecule may be conducted in the absence of a diluent with an efficient separation of olefin products from the paraffin recycle stock.

From the standpoint of chemical and physical characteristics, the most desirable diluent for dehydrogenation is water vapor. This diluent may be cheaply provided in any desired amount and may be removed from the hydrocarbon stream by simple condensation, thereby eliminating a large part of the compression and fractionation equipment necessary when other diluents are used. Steam has been used as a feed diluent in several different types of catalytic and thermal processes for hydrocarbon conversion such as cracking and olefin dehydrogenation. In such processes, particularly those in which solid catalysts are used, the steam serves not only as a diluent, but also as a reagent for the removal of carbon that deposits on the catalyst.

As mentioned hereinbefore, the use of water vapor has previously been condemned in the art because of its deleterious effects on the activity of conventional catalysts employed for the dehydrogenation of paraffins. The catalysts now used for the dehydrogenation of paraffins in commercial operations show poor conversion when steam is used as a diluent. Present practice is to dehydrogenate undiluted paraffins or to use a

non-aqueous gaseous diluent. The feed stream is carefully dehydrated to eliminate all but traces of water vapor.

Steam dilution of feeds to dehydrogenation processes has been applied chiefly to olefins, from which diolefins are produced. The catalysts preferred for dehydrogenation of olefins are different from those preferred for dehydrogenation of paraffins; in fact, when steam-diluted olefinic feeds are treated under preferred conditions in the presence of preferred catalysts for the production of diolefins, any paraffins present in such feeds are, in many cases, substantially unreacted (see Schulze et al., U. S. 2,367,623).

Catalysts have recently been devised in contact with which paraffins may be effectively and efficiently dehydrogenated in the presence of major amounts of steam, as is disclosed in application Serial No. 683,996, now Patent No. 2,500,920, filed July 16, 1946, of which I am one of the joint inventors. The catalysts disclosed therein consist essentially of a major proportion of alumina and minor amounts of one or more of the oxides of molybdenum, tungsten, and vanadium. It is also disclosed that these catalysts may be further improved by the addition of from 1 to 15 weight per cent chromium oxide.

I have now found that catalysts consisting essentially of alumina and the above enumerated dehydrogenating oxides, in which the alumina is in minor amount by weight of the composite catalyst, have substantially longer life than catalyst composites of the same constituents but in which the alumina is present in major proportions.

An object of this invention is to provide an improved process for the production of olefins and diolefins from corresponding paraffins. Another object of the present invention is to provide a process for the dehydrogenation of paraffins wherein steam or water vapor may be effectively and efficiently employed as the diluent. A more specific object is to provide a process which is particularly applicable to the dehydrogenation of butane to produce butylenes and butadiene. It is also an object of the invention to provide catalysts for the conversion of paraffins to olefins and diolefins in the presence of water vapor as a diluent, which catalysts maintain higher conversion activity for longer periods of time than catalysts heretofore known. Still another object of the present invention is to provide catalysts which give efficient conversion of paraffins to olefins and diolefins in the presence of water vapor as a diluent. Other objects and advantages will become apparent to those skilled in the art from the accompanying disclosure of the invention.

It has been found that paraffins may be advantageously dehydrogenated in the presence of steam as a diluent to produce olefins and diolefins. Advantages obtained by steam dilution are longer reaction cycles, obviation of the necessity for using reactors made of special heat and corrosion resistant alloys, and the feasibility of using comparatively large reactors. The longer reaction cycles result from the chemical reaction of steam on deposited carbon, known as the water gas reaction, which enables the catalyst to be used for long periods without regeneration with an oxygen-containing gas. Large reactors of the bed type, in contrast to reactors comprising complex heat exchange systems, may be employed in this process as a result of the heat-carrying capacity of steam. This represents a tremendous saving in investment and operating costs.

It has also been found that catalysts that are

satisfactory for the dehydrogenation of undiluted paraffins are relatively unsatisfactory for the dehydrogenation of paraffins diluted with steam because of low yields and short process cycles. It has been further found that a catalyst containing a major portion of alumina and a minor proportion of at least one oxide of the group molybdenum oxide, tungsten oxide, and vanadium oxide is satisfactory for dehydrogenating paraffins diluted with steam. The catalysts of the present invention consist essentially of a minor amount of alumina, preferably in the range of 10 to 45 per cent by weight of the composite and the balance at least one, and preferably more than one, of the oxides of molybdenum, vanadium, and tungsten, each in the amount of at least 5% of the weight of the catalyst. While a catalyst of alumina and chromia alone is unsatisfactory for dehydrogenating in the presence of steam, it is desirable to incorporate from 1 to 80 weight per cent, preferably 5 to 50 weight per cent, of chromia in a catalyst composition of alumina and one of the oxides just named. Preferred combinations of these dehydrogenating metals in combination with alumina are chromia-vanadia, chromia-molybdena, and vanadia-molybdena. These catalysts are especially effective and efficient in the dehydrogenation of paraffins diluted with steam in large amounts and have considerably longer life before regeneration is required than catalysts containing the same constituents with a major proportion of alumina.

The catalysts of this invention may be prepared by any of the methods of preparing solid porous oxide catalysts known in the art. Such methods include mixing of the powdered nongel components, coprecipitation of the components as gel, and impregnation of the carrier material, i. e., aluminum oxide, with an aqueous solution of a salt of the other metal, with subsequent ignition to the oxide. An example of the latter method of preparation is the use of an aqueous solution of a molybdenum salt, preferably ammonium molybdate, to impregnate a porous alumina carrier, suitably in the form of small pellets, followed by ignition to molybdenum oxide by passing an oxygen-containing gas over the catalyst at a moderately elevated temperature. Catalysts of the invention may also be prepared by coprecipitating the hydrous oxides from mixed aqueous solutions of their salts so as to form a composite with less than the desired amount of one or more of the constituents and, after forming the composite into pellets, adding the remainder of said constituent by single or multiple impregnation with a suitable salt solution followed by calcination to convert to the oxide. The catalyst may be used in the form of granules of approximately 5 to 60 mesh size, in the form of pills or pellets, in the form of fluidized powder, or in the form of dust suspended in the feed.

In the operation of the present invention the paraffin feed, e. g., normal butane, is admixed with steam in the ratio of between 1 to 1 and 1 to 30. The mixture is heated to the conversion temperature and passed into contact with the catalyst. The effluent from the dehydrogenation zone may be processed in known manner for the separation of substantially pure olefins and diolefins. The olefins may be separately dehydrogenated in a known manner for conversion to diolefins. Unconverted paraffins are recycled to the dehydrogenation step. If desired, the diolefins 75 may be separated from the effluent and the

olefins together with unreacted paraffins recycled to the dehydrogenation step.

Preferred conditions for dehydrogenation of steam diluted paraffins in accordance with this invention are: temperature, 1000-1400° F.; absolute pressure 1-3 atmospheres; volume ratio of steam to hydrocarbons of 1:1 to 30:1, preferably 10 to 25 volumes of steam per volume of hydrocarbon; hydrocarbon space velocity 200-700 gaseous volumes (S. T. P.) per volume of catalyst per hour. The hydrocarbon and the steam may be mixed before charging to the reaction zone or the steam may be separately injected at a plurality of points along the reaction zone. The steam is preferably preheated to a temperature at least as high as the temperature employed in the reaction and in some cases it may be preferable to separately preheat the hydrocarbons and the steam before mixing. It is sometimes desirable to preheat the steam to a temperature somewhat above the desired conversion temperature and to admix the preheated steam with preheated paraffin at a temperature slightly below the desired reaction temperature such that the resulting mixture attains the reaction temperature. The effluent from the reaction zone is cooled to condense and remove steam, and the individual hydrocarbon components are separated by conventional methods such as fractionation, solvent extraction, and so forth. When the activity of the catalyst becomes undesirably low because of carbon depositions, the flow of hydrocarbons is interrupted, and steam is allowed to contact the catalyst until the carbon is removed. Air may be added to the steam during the regeneration period if desired.

In order to illustrate specific advantages of the invention, three catalysts containing minor amounts of alumina and major amounts of the dehydrogenating metal oxides disclosed, and one of the catalysts of the aforementioned application containing a major amount of alumina were utilized under comparable reaction conditions in a butane dehydrogenation process in the presence of considerable steam. All of the catalysts were in the form of one-eighth inch by one-eighth inch cylindrical pellets. In the several runs the steam was admixed with normal butane, the mixture preheated to the conversion temperature and passed over the pelleted catalyst. The effluent was condensed and analyzed. The space velocity is expressed in terms of volumes of normal butane per volume of catalyst per hour. The total conversion per pass represents the percentage by volume of normal butane reacted in passing over the catalyst. The yield of normal butylenes and butadiene per pass represents the percentage by volume of the normal butane feed which was converted to these products in passing over the catalyst. The ultimate yield indicates the percentage by volume of normal butane reacted which was converted to these products and is a measure of the efficiency of the catalyst for conversion of the feed to the desired products. Reaction conditions and results obtained are shown in Table I.

Table I

Catalyst	Temp., F.	Space Velocity Butane, Vol./Vol./ hr.	Vol. Ratio Steam to Butane	Total Conver- sion, Per Cent	Yield of $nC_4H_6 + C_4H_4$, Mol Per Cent		Per Cent of C_4H_6 in $C_4H_6 + nC_4H_4$
					per pass	ultimate	
A-----	1,193	722	18.8	24.22	14.82	61.19	26.8
B-----	1,199	719	18.9	25.29	15.66	61.92	40.2
C-----	1,200	661	20.2	23.48	13.00	55.37	27.2
D-----	1,188	739	18.7	20.64	10.98	53.20	40.3

The compositions of the catalysts shown in Table I are as follows: Catalyst A consisted of 60% alumina, 30% vanadia, and 10% chromia. (All per cents are by weight.) Catalyst B consisted of 25% alumina, 50% chromia, and 25% vanadia. Catalyst C consisted of 42% alumina, 40% chromia, and 18% vanadia. Catalyst D consisted of 38% alumina, 47% chromia, and 15% vanadia. All of the catalyst composite of catalysts A and B and the major portion of the catalysts C and D were prepared by precipitating the hydrous oxides from mixed solutions of chromium and aluminum nitrates and vanadium pentoxide dissolved in hydrogen peroxide by addition of 3 per cent aqueous ammonia followed by recovering the precipitate and treating in the usual manner in order to form the composite into pills consisting of the metal oxides. Catalyst C was made by impregnating the co-precipitated composite in the form of pellets three times with 30 per cent chromium trioxide solution so as to deposit 23 per cent of chromium oxide; and catalyst D was made in a similar manner by impregnating six times with 30 per cent chromium trioxide solution so as to deposit an additional 37 per cent chromium oxide thereon.

The rates of activity decline of the various catalysts tested during the dehydrogenation cycle are shown in Table II.

Table II

Catalyst	Catalyst Activity During Cycle; Time in Hours After Start of Cycle				
	0.5 hr.	2 hrs.	4 hrs.	6 hrs.	8 hrs.
A-----	28.5	24.6	19.3	15.0	-----
B-----	28.8	27.2	25.8	-----	-----
C-----	29.4	27.8	26.4	26.2	-----
D-----	28.8	26.3	25.9	25.7	24.9

The catalyst activity readings in the above table are those recorded by a thermal-conductivity hydrogen-sensitive gas analyzer and are approximately 2-5 units above the total hydrocarbon conversion.

It can be seen from the data in Table I that the efficiency of the catalysts of this invention containing minor amounts of the aluminum oxide compare very favorably with similar compositions which include a major amount of alumina in their composition. It should also be noted that the amount of conversion to butadiene is considerably higher for the lower content alumina catalysts. However, the outstanding advantage of the catalysts of the invention in the dehydrogenation of paraffin hydrocarbons to olefins and diolefins in the presence of relatively large proportions of steam is shown in the data in Table II, which clearly indicate that catalysts containing minor amounts of alumina in combination with the dehydrogenating metal oxides have at least as high initial activity and maintain their activity at a high level over longer dehydrogenation periods than catalysts containing a major amount of alumina and the same

metal oxide dehydrogenating catalyst. This is a highly desirable characteristic since the on-stream dehydrogenating cycle can be substantially increased so as to reduce the number of regeneration periods required and, therefore, substantially increase the yield per day from a given amount of catalyst.

Certain modifications of the invention will become apparent to those skilled in the art and the illustrative details disclosed are not to be construed as imposing unnecessary limitations on the invention.

I claim:

1. A process for the dehydrogenation of an aliphatic paraffin hydrocarbon which comprises contacting said hydrocarbon diluted with from 1 to 30 volumes of steam per volume of hydrocarbon under dehydrogenating conditions, including a temperature within the range of 1000° F. to 1400° F. with a catalyst consisting essentially of alumina in the range of 10 to 45 weight per cent of the catalyst and the balance of at least one oxide selected from the group consisting of molybdenum oxide, tungsten oxide, and vanadium oxide.

2. The process of claim 1 in which the catalyst also contains at least 5 weight percent chromium oxide.

3. A process for the dehydrogenation of an aliphatic paraffin hydrocarbon containing from four to five carbon atoms per molecule which comprises passing said hydrocarbon in admixture with from 1 to 30 volumes of steam per volume of hydrocarbon under dehydrogenating conditions, including a temperature within the range of 1000° F. to 1400° F. into contact with a catalyst consisting essentially of aluminum oxide in the range of 10 to 45 weight per cent and the balance of chromia and at least one oxide selected from the group consist-

ing of molybdenum oxide, tungsten oxide, and vanadium oxide.

4. The process of claim 1 in which said catalyst includes at least 5 weight per cent vanadia.

5. The process of claim 1 in which said catalyst includes at least 5 weight percent molybdena.

6. The process of claim 3 in which said catalyst includes at least 5 weight per cent vanadia.

7. The process of claim 3 in which said catalyst includes at least 5 weight per cent molybdena.

8. A process for the dehydrogenation of an aliphatic paraffin hydrocarbon containing from four to five carbon atoms per molecule which comprises passing said hydrocarbon in admixture with from

15 1 to 30 volumes of steam per volume of hydrocarbon under dehydrogenating conditions, including a temperature within the range of 1000° F. to 1400° F. into contact with a catalyst consisting essentially of aluminum oxide in the range of 10 to 45 weight per cent, chromium oxide in the range of 5 to 50 weight per cent, and at least 5 weight per cent of an oxide selected from the group consisting of molybdenum oxide, tungsten oxide, and vanadium oxide.
